CLAIM

We claim the ornamental design for data capture device, as shown and described.

DESCRIPTION

FIG. 1 is a front perspective view of an example data capture device;

FIG. 2 is a rear perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof; and,

FIG. 8 is a bottom view thereof.

Broken lines are for purposes of illustrating environment and form no part of the design claimed.
